CLAIM

We claim the ornamental design for the pivot for a tool, as shown and described.

DESCRIPTION

FIG. 1 is an isometric view of a pivot for a tool;
FIG. 2 is a front view of the pivot for a tool shown in FIG. 1;

FIG. 3 is a top view of the pivot for a tool shown in FIG. 1, with the bottom view being the same as FIG. 3;
FIG. 4 is a left side view of the pivot for a tool shown in FIG. 1; and,

FIG. 5 is a right side view of the pivot for a tool shown in FIG. 1.

The broken lines showing portions of the tool in FIGS. 1-5 are for illustrative purposes only and form no part of the claimed design.

The rear elevational view of the article not shown in the drawing or described in the specification forms no part of the claimed design.
